REFRIGERATED CABINET AND DISPLAY SHELF UNIT

Herman Zaslovsky, 30 Massapequa Ave., Massapequa,
N.Y., and Harry Rosenfeld, 818 E. Chester St., Long
Beach, N.Y.

Filed Oct. 17, 1963, Ser. No. 77,021

Term of patent 3½ years

(Cl. D80—11)

FIG. 2

FIG. 3

FIG. 4

FIG. 5

FIG. 6

FIG. 1 is a perspective elevational view of a refrigerated cabinet and display shelf unit embodying our new design.

FIG. 2 is a front elevational view thereof.

FIG. 3 is a top plan view thereof.

FIG. 4 is a side elevational view thereof.

FIG. 5 is a rear elevational view thereof.

FIG. 6 is a side elevational view of the side opposite that shown in FIG. 2.

It is to be understood that the perforations fragmentarily shown on the rear panel are continuous throughout the entire surface of the panel.

We claim:

The original design for a refrigerated cabinet and display shelf unit, as shown and described.
